UNITED STATES PATENT OFFICE.

JACOB C. BAUER, OF PHILADELPHIA, PENNSYLVANIA.

FLAP-RETAINER FOR PAPER BOXES.

SPECIFICATION forming part of Letters Patent No. 296,510, dated April 8, 1884.

Application filed January 23, 1884. (No model.)

To all whom it may concern:

Be it known that I, JACOB C. BAUER, a citizen of the United States, and a resident of Philadelphia, Pennsylvania, have invented an improvement in Flap-Retainers for Paper Boxes; and I do hereby declare the following to be a full, clear, and exact description of the same.

My invention consists of the combination of the two outer flaps of a paper box with a retainer attached to one of the flaps, and admitting of being moved over the other flap when it has to be secured, and moved back clear of the same when it has to be opened.

In the accompanying drawings, Figure 1 is a perspective view of one end of a paper box, showing the inner flaps closed and the under side of the movable retainer on one of the outer flaps; Fig. 2, a view showing the inner flaps and one of the outer flaps closed; Fig. 3, a perspective view, showing both outer flaps closed, but not fastened; and Fig. 4, a view showing the outer flaps closed and secured by the retainer.

The body A of the box is quadrangular, and as both ends may be alike, one end only is shown in the drawings. There are two inner flaps, a a', (shown in Fig. 1,) and two outer flaps, b b', and to either of the latter flaps may be adapted the sliding retainer B, which consists, preferably, of a strip of thin metal extending across the outer face of the flap, the end portions of the strip being bent against

the inner or rear face of the flap. The retainer may consist of a continuous loop of metal or other available material; but no matter how the retainer is constructed it must be such that it can be moved freely on the flap to which it is attached. The outer flap b must be of such a length that when folded down a portion of the under flap b' carrying the retainer will be exposed, as shown in Fig. 3, prior to fastening the outer flap b, or when the latter has to be opened. When the outer flap b has to be secured to the flap b', all that is necessary is to move the retainer over the flap b, as shown in Fig. 4, and when the latter flap has to be released the retainer must be moved back so as to be clear of the edge of the said flap, as shown in Fig. 3.

The inner flaps may be dispensed with when the box has to be used for containing articles or material which will not be liable to escape from the box in the absence of these flaps.

I claim as my invention—

The combination of the outer flaps, b and b', of a paper box, with a retainer, B, applied to one flap and being movable over and off from the other flap, substantially as described.

In witness whereof I have hereunto set my hand in the presence of two subscribing witnesses.

JACOB C. BAUER.
